UNITED STATES PATENT OFFICE.

ARVID A. DANIELSON, OF MANNING, IOWA, ASSIGNOR TO DULTMEIER MANUFACTURING COMPANY, OF MANNING, IOWA.

HITCH.

1,401,764.

Specification of Letters Patent. Patented Dec. 27, 1921.

Application filed August 23, 1920. Serial No. 405,432.

To all whom it may concern:

Be it known that I, ARVID A. DANIELSON, a citizen of the United States, and a resident of Manning, in the county of Carroll and 5 State of Iowa, have invented a certain new and useful Hitch, of which the following is a specification.

The object of my invention is to provide a hitch especially designed for hitching a 10 vehicle to a tractor, or the like, which is of simple, durable and inexpensive construction.

More particularly it is my object to provide in such a device a hitch that will be capable of permitting up and down movement of the tongue, and to permit some longitudinal movement of the tongue. The parts being so arranged that the tongue will not be capable of rotary or sideward movement; yet the parts will permit such movement and play that is ordinarily necessary when several wagons, or the like are hitched together.

Still a further object is to provide in such 25 a device an adjustable hound, which has fixed thereon a tongue receiving socket. The socket being so designed that the end of a short tongue may be placed therein, instead of the ordinary implement tongue. The 30 short tongue being provided at its forward end with my improved hitch device.

With these and other objects in view, my invention consists in the construction, arrangement and combination of my device, 35 whereby the objects contemplated are attained, as hereinafter more fully set forth, pointed out in my claims, and illustrated in the accompanying drawings, in which:

Figure 1 shows a top plan view of the 40 adjustable hound and tongue receiving socket.

Fig. 2 shows a central, sectional view taken on line 2—2 of Fig. 1.

Fig. 3 is a transverse, central, sectional 45 view taken on line 3—3 of Fig. 1.

Fig. 4 is a transverse, central, sectional view taken on line 4—4 of Fig. 1.

Fig. 5 is a perspective view of the tongue with the hitch thereon; and

50 Fig. 6 is an enlarged perspective view of the hitch.

In the accompanying drawings I have used

the reference numeral 10 to indicate an ordinary fixed stub tongue member, which is provided with a slot 11 through which is extended the queen bolt 12.

The stub tongue 10 is provided on both of its sides with the forwardly extending arms 13, which are fixed to the stub tongue 10 by means of the bolts 14.

Plates 15 and 16 are provided which cover the end of the stub tongue 10 and a portion of the arms 13. The plates 15 and 16 are provided with registering openings through which are extended the bolts 17.

The bolts 17 tend to hold the arms 13 to the stub tongue 10.

Fixed to the arms 13 near their forward ends is an upper plate 18 and the lower plate member 19. The lower plate member 19 is provided with a yoke portion which is substantially the same width as the distance between the two arms 13.

The plate 16 is flared slightly downwardly as illustrated in Fig. 2 of the drawings.

The plates 18 and 19 are held together against the upper and lower surfaces of the arms 13 by means of the bolts 20.

From the construction of the parts just described it will be seen that a socket portion A is formed between the plates 15 and 16, the plates 18 and 19 and the two arms 13.

Received within the socket portion A so formed, is a tongue member 21, which is provided with the inclined under side 22. The inclined side 22 is received within the socket and rests against the flared portion of the plate 16.

Openings 23 are provided in each of the plates 18 and 19 and register with each other. An opening 24 is provided in the tongue member 21 which coincides with the opening 23. When the tongue is installed within the socket A, the openings 23 and 24 are designed to receive a king bolt.

The hound comprises a pair of hound members 25 which are placed on either side of the stub tongue 10 and are held against movement by means of the pairs of links 26 and 27.

The pairs of links 26 and 27 are pivoted to the clamping members 28 and 29. Each of the clamping members 28 and 29 are slidably mounted on the stub tongue 10 so that

when the clamping members 28 and 29 are moved they will cause the hound members 25 to move.

Braces 30 are pivoted to the arms 13 and 5 to the hound members 25. The braces 30 as well as the links 26 and 27 are composed of two members spaced from each other and one above another so that one will lie substantially parallel with the upper surface 10 of the tongue 10, while the other one will be substantially parallel with the lower surface.

Each of the clamping members 28 and 29 are composed of an upper and lower member, 15 and are provided with the shoulders 31, which rest on either side of the stub tongue 10.

Each of the clamping members are provided with lugs 32, which are designed to 20 co-act with the stub tongue 10 and thus prevent any possible movement.

Bolts 33 are provided for holding the clamping members together, and for holding the pairs of links 26 and 27 to the clamping 25 members.

Bolts 34 are provided for holding the pairs of links 26 and 27 to the hound members 25.

The bolts 35 extend through the arms 13 and hold the braces 30 on the arms 13. The 30 tongue 21 is provided near its forward end with a slot or groove 36 in which is received the plate 37 and held in position by means of the rivets 38.

The plate 37 has its forward end curved, 35 and is extended beyond the forward end of the tongue 21.

A clevis device 39, which is substantially U shaped is provided with a slot 40 between its ends. The extended end of the plate 37 40 is received in the slot 40.

A bolt 41 is fixed in the plate 37 and is received between the two sides of the clevis or U shaped member 39.

The curved portion 42 of the U shaped 45 member 39 will prevent the removal of the U shaped member 39 while the bolt 43 will prevent the removal from the other side of the U shaped member 39.

The bolt 43 is provided with a nut 44. 50 The bolt 43 is designed to be received in an opening in an ordinary draw bar of a tractor, or the like, a portion of the draw bar being received between the ends of the U shaped member 39.

It will be seen that the tongue 21 will be 55 capable of pivotal movement on a vertical axis, the bolt 43 permitting such movement.

The slot 40 will permit longitudinal movement of the tongue relative to the remainder 60 of the device, while the bolt 41 will permit up and down movement of the parts.

It is extremely necessary that such movement be permitted in order to provide a successful hitch device.

The slot 40 will prevent any sideward 65 movement of the plate 37, as clearly illustrated in Figs. 5 and 6 of the drawings.

The advantages of my device are that I am able to readily and easily secure the hitch to a draw bar and the parts will be 70 permitted to move in various directions, yet providing a very efficient hitch.

The hitch is held rigid against movement in certain directions, while a substantially 75 flexible connection will be had.

It will be understood that the socket A may receive an ordinary implement tongue when it is not desired to draw the vehicle 80 by a tractor.

It is my purpose to cover by my claims 85 any changes or modifications in the construction of my hitch, and any use of mechanical equivalents, which may be reasonably included within their scope.

I claim as my invention:

1. In a device of the class described a fixed tongue member having a pair of arms fixed to its sides near its forward end, a pair of plates fixed above and below said arms near their rear ends, the lower of said plates being slightly inclined, a second pair of plates fixed above and below said arms near their forward ends, one of said last plates being bent U shaped so as to have its center spaced from the upper plate a greater distance 95 than the thickness of said arms, the parts being so arranged that said arms and said pairs of plates form a socket for receiving the rear end of a tongue having its under surface tapered as and for the purposes 100 stated.

2. In a device of the class described a fixed tongue member having a pair of arms fixed to its sides near its forward end, adjustable hound members secured to said fixed tongue member and to said arms, a pair of plates fixed above and below said arms near their rear ends, the lower of said plates being slightly inclined, a second pair of plates fixed above and below said arms near their forward ends, one of said last plates being bent U shaped so as to have its center spaced from the upper plate a greater distance than the thickness of said arms, the parts being so arranged that said arms and said pairs of plates form a socket for receiving the rear end of a tongue having its under surface tapered as and for the purposes 110 stated.

Des Moines, Iowa, August 3, 1920.

ARVID A. DANIELSON.
